UNITED STATES PATENT OFFICE

EARL A. WHEELER, OF LOS ANGELES, CALIFORNIA, ASSIGNOR TO STANDARD ROAD MAINTENANCE COMPANY, OF LOS ANGELES, CALIFORNIA, A CORPORATION OF NEVADA

ROAD SCRAPER

Application filed July 12, 1926. Serial No. 121,835.

This invention relates to road scrapers and is more particularly directed to a road scraper or planer adapted for use in scraping or planing surfaced roads to remove surface irregularities, such as bumps and the like.

In the scraping or planing of roads, particularly roads formed of a concrete or like base and having a surface of asphaltum or like material, it is essential that there be provided a machine in which the scraping and planing means may be accurately adjusted to the crown of the road and that means be provided for gradually breaking large ruts, bumps or projections of this surface covering so that the entire planing mechanism does not come into contact with the said irregularities at once. The contacting of the planing or scraping mechanism with these irregularities at one time results in the breaking of the bond between the surface covering of asphalt or the like and the base of concrete or the like, so that the surface covering may be bodily removed from the road and the scraper or planer does not act to cut away the irregularities.

It is therefore an object of this invention to provide an apparatus for scraping or planing roads, in which means are provided for cutting in steps or gradually the irregularities from the surface of the roadway so that at no time does the cutting or planing mechanism come into straight line contact transverse to the road with the irregularity so as to tend to break the bond between the surface covering of the road and the base thereof, and in which apparatus means are provided for accurately adjusting the planing mechanism to the contour of the crown of the road.

Another object of this invention is to provide means for locking individual cutting teeth in position in the planing mechanism so that the same will not become loosened during the planing operation.

Another object of this invention is to provide a frame in which the planing mechanism is mounted, and which frame is adjustable relative to the frame of the road scraper so as to permit adjustment of the planing mechanism to correspond with the crown of the road, and which frame is so constructed that

when the same is adjusted relative to the frame of the road scraping machine, the said frame, and hence the cutters or planers mounted therein will not be permitted to move transversely relative to the frame of the road scraper but will be firmly held and maintained therein.

Another object of this invention is to provide an apparatus for carrying out the aforesaid objects that is of simple and inexpensive construction and which may be easily and accurately manipulated.

Other objects and advantages of this invention will be apparent from the following detailed description of a preferred embodiment thereof as illustrated in the accompanying drawings, in which drawings:

Figure 1 is a top plan view of a road scraper embodying this invention.

Figure 2 is a top plan view of the scraper or planer mechanism embodied in this invention, illustrating the control mechanism for adjusting the frame thereof relative to the frame of the road scraper as broken away.

Figure 3 is a front elevation thereof taken substantially on the line 3-3 of Figure 1.

Figure 4 is a fragmental side elevation thereof.

Figure 5 is a fragmental sectional view of the control mechanism for regulating the adjustment of the planer frame relative to the frame of the road scraper.

Figure 6 is a fragmental sectional view illustrating means embodied in this invention for locking the teeth within the planer frame.

Figure 7 is a sectional top plan view thereof taken substantially on the line 7-7 of Figure 6.

In the preferred embodiment of this invention, illustrated in the accompanying drawings, 1 illustrates spaced apart frame members which may be of any desired or preferred construction, such, for example, as illustrated in my copending application for road working machine, filed December 10, 1925, Serial No. 74,450. The spaced frame members 1 are secured together at their ends by transversely extending frame members 2 and 3, platform 4, the adjustable frame units

5 and 6, the disc adjustment frames 7 and 8 and the scraper blade frame unit 9, all of which construction may be as illustrated in my copending application above referred to 5 or may be of any other desired or preferred construction.

The adjustable frame unit 5 provides means for adjusting the forward end of the spaced frame members 1 on the wheels 10 relative to the surface of the roadway. The adjustable frame unit 7 provides means for forming a complete or entire adjustment of the disc cutters 11 relative to the surface of the highway or road. The adjustable frame 15 unit 8 forms a means for adjusting the angular position of the discs 12 relative to the surface of the highway, and which discs 12 may be employed for the purpose of breaking up the material cut by the planer mechanism 20 13 which will hereinafter be described. The adjustment frame 9 provides a means for adjusting the relation of the scraper blade 10^a relative to the surface of the road which scraper blade 10^a is for the purpose of scraping and removing from the surface of highway all minor irregularities so as to leave a perfectly smooth surface thereon and for placing the material cut by the other cutting members of the road scraper to one side thereof and through an opening 14. The frame 25 mechanism 6 provides a means for adjusting the wheels 15 of the road scraper relative to the surface of the highway so as to adjust the position of the rear ends of the frame members 1, all of which adjustment frames and scraper mechanisms are fully described 30 in my copending application above referred to.

The planer mechanism, to which this invention is particularly directed, comprises a frame 16 in which the planer mechanism formed by the teeth 17 is mounted. The planer mechanism is preferably of the shape of a V-shaped wedge so that the forward 40 tooth or cutter 18 enters the projection, bump or the like in the road surface prior to the entrance into the bump projection or irregularity of the road surface of the immediate adjacent teeth lying to the rear thereof. This 45 manner of mounting the planer teeth provides a planer which forms a cut progressively increasing in width, the advanced tooth 18 forming an opening or line of cleavage into which the following teeth 19, 20, etc. 50 follow. By this means, the teeth are prevented from entering the surface irregularity as a unit, overcoming the tendency inherent in planer mechanisms as heretofore commonly employed, to break the bond between 55 the road surface covering of asphalt and the like and the concrete or like material base. The planer mechanism provided by the teeth 18, 19, 20, etc. cuts a regular and smooth cut over the surface of the road without danger of breaking the bond between the 60

covering and the base of the road at any point.

The frame 16 is preferably formed as a casting having a front transverse section 21 which connects with the front corner sections 22 and which is formed with inwardly diverging sections 23 which terminate in a central tooth supporting section 24, which central tooth supporting section 24 branches outwardly from the center thereof in sections 25 along which cutting teeth of the planer cutter are mounted, and which sections 25 terminate in rearward corner sections 26.

At each corner of the frame 16, there is secured to the frame members 1 a post 27, 80 which post 27 may be secured to the frame members 1 by any suitable or desirable means, such as the bolts 28. The posts 27 are adapted to be engaged on their adjacent surfaces by means of adjustment guide blocks 29, which are mounted in position at the forward ends 22 of the frame 16, and at their rearward end by transversely extending guide projections 30. The guide projections 30 have mounted on their engaging surfaces by means of pins 90 31 hardened steel blocks 32 which form the engaging or bearing surfaces between the posts 27 and the frame 16 at the rear corners. The bearing blocks 29 at the forward end of the frame are provided with like hardened steel bearing strips 33. The bearing blocks 29 are adjustably secured in position to the frame 16 by means of bolts 34 which pass through slots 35 formed in the end sections 22 and by means of lock bolts 100 36 which are screw-threaded into the lateral projections 37 formed on the end sections 22 so as to adjust the bearing blocks 29 to firmly secure the frame 16 between the posts 27.

In order to permit angular adjustment of the frame 16 and hence the planing cutter 17 relative to the frame members 1, the forward end sections 22 of the frame 16 are formed curved as illustrated at 38, (see Figure 3). At the center of the arc of which curve 38 is formed are the pivot pins 39, by means of which the frame 16 is adjustably supported as will hereinafter be pointed out.

Means are provided for holding the frame 16 from moving laterally between the frame members 1, which means are preferably of the following construction:

The frame 16 at its forward ends 22 is curved, as illustrated at 38. The rear ends 23 of the frame 16 are also curved to provide engaging surfaces 40. The center of the radii of the curves upon which the curved surfaces 38 and 40 are formed is the pivot point from which the frame 16 is supported. This manner of construction insures that at all times the surfaces 38 and 40 will be engaged with the inner surfaces of the frame members 1 or the appended parts of the frame members 1 such, for example, as the forward posts 27. The frame 16 being at all times engaged be- 125 130

tween the frame members 1, it is not possible for the same to move transversely between the frame members 1 and, therefore, the planer members carried by the frame 5 16 are prevented from oscillating as they perform their planing function.

Means are provided for accurately adjusting the planer frame 16 to adjust the planer cutter 17 to the exact crown of the roadway 10 or surface over which the scraper is being drawn. This adjustment is particularly important in the scraping of road surfaces which are bonded to a base in order that there 15 may be removed from the surface only that amount of the surface material that is absolutely necessary in order to provide a smooth surface-way. Accuracy of adjustment in this operation is so important that it is generally customary to provide two workers 20 to adjust the frame of this machine during the time it is being operated. One of the workers is employed in adjusting one side of the planer cutter 17 to the crown of the road while the other is employed in adjusting the 25 position of the opposite side of the planer cutter 17 relative to the surface of the road. In order to obtain this accurate adjustment I prefer to employ the following means:

Mounted upon the upper extension of the 30 posts 27 are transversely extending adjustment frame members 41 and longitudinally extending connecting frame members 42 and a central connecting frame 43. Mounted upon the central connecting frame 43 are gear 35 housings 44, in each of which gear housings 44, there is mounted a bevel gear 45 which is keyed to the shaft 46, to the upper end of which shaft 46 is secured an operating wheel 47. The shaft 46 is journaled in a bearing 40 provided by the base-plate 48 and a bearing provided by the gear housings 44 and the shaft 46 is maintained against endwise motion by means of collars 49 which are secured to the shaft 46.

45. Mounted in bearings 50, supported within the gear housing 44, are shafts 51 and 52, which shafts 51 and 52 extend from the gear housing 44 to corner gear housings 53 and 54. Mounted on the ends of the shafts 51 and 52 50 within the gear housing 44 are beveled gears 55 and 56, both of which mesh with the beveled gear 45.

Each of the operating wheels 47 controls the adjustment of one side of the planer frame 55 16 from the opposite corners thereof by substantially the same means so that only one of these means will be described. The shaft 51, for example, is journaled in a bearing supported in the gear housing 53 and the gear 57 60 is secured to the shaft 51 within the housing 53 in position to mesh with a gear 58, which gear 58 is keyed or otherwise secured to a threaded box 59, through which box 59 a screw 60 is threaded. The screw 60 extends 65 through the gear housing 53 and at its lower

end is provided with an eye 61 through which a pin 62 extends. The pin 62 is screw-threaded into the frame 16 and the eye 61 extends into a slot or recess 63 formed in the respective corner of the frame 16.

The planer cutter 17 is preferably composed of a plurality of cutter bars 64 which are provided with sharpened planing points 65, each of which bar cutters 64 is mounted within a recess formed in the cutter frame 16 so as to present a continuous wedge shape cutting edge where the same engages the road surface, with the possible exception of the space provided between the forward cutters 18 and 19 and the opposite rearwardly positioned and outwardly staggered cutters 20.

Means are provided for locking the bar cutters 64 firmly in position within their respective recesses formed in the cutter frame 16, which means are preferably of the following and similar construction for each of the bar cutters 64 so that only one thereof will be described.

The bar cutter 64 is mounted within a recess 66 formed in the cutter frame 16 and a pair of bolts 67 pass through boxes formed adjacent the recesses 66 and which bolts 67 pass through engaging blocks 68 which have inner engaging surfaces 69 formed to the contour of the shanks of the bar cutter 64. 65 Mounted at the rear of the recesses 66 are chamfered block members 70 which comprise heads 71 having chamfered engaging ends 72 and shanks 73 which fit within bores 74 formed in the frame 16 immediately at the rear of the recesses 66. Nuts 75 are screw-threaded to the bolts 67 so as to clamp the engaging blocks 68 into engagement with the shanks of the bar cutters 64. By this means, the shanks of the bar cutters 64 are firmly clamped and locked in position within their respective recesses 66 so as to prevent vertical displacement of the base 65 and so as to insure an even cutting surface of the planer cutter 17.

It will be obvious from the foregoing that I have provided a road scraper in which a planer is mounted which may be accurately adjusted to the crown of the road, and which planer cutter is firmly maintained in position between the frame members 1 of the road scraper so as to be practically laterally immovable, and in which planer there is provided a wedge shaped cutter composed of a plurality of cutting members, the forward of which will cut a path through projections or bumps formed in the road surface so that each of the rearwardly succeeding cutting members will only cut its portion of the bump or projection away and will not tend to remove the road surface covering from the base.

Having fully described a preferred embodiment of my invention, it is to be understood that I do not wish to be limited to the ex- 130

act details herein set forth, which may obviously be varied without departing from the spirit of my invention as set forth in the appended claims.

5 I claim:

1. In a road scraper, the combination of a pair of spaced frame members, a planer frame mounted intermediate the said frame members, means for separately adjusting the 10 sides of the planer frame relative to the said frame members, and the said planer frame being formed at its sides so as to engage the said frame members in any adjusted position to prevent relative lateral movement of the 15 planer frame and the said frame members.

2. In a road scraper, the combination of a pair of spaced frame members, a planer frame mounted intermediate the said frame members, means mounted on the said frame 20 members for pivotally adjusting the opposite sides of the planer frame vertically relative to the said frame members, and the said planer frame being formed curved at its sides so as to engage the said frame members 25 in any adjusted position to hold the said planer frame from lateral movement relative to the said frame members.

3. In a road scraper, the combination of a pair of spaced frame members, a planer 30 frame mounted intermediate the said frame members, cutter teeth supported by and arranged in V-shape upon the said planer frame, and means mounted on the said frame members and pivotally connected at opposite 35 sides of the said planer frame for independently adjusting the opposite sides of the planer frame vertically relative to the said frame members.

4. In a road scraper, the combination of a 40 pair of spaced frame members, a planer frame mounted intermediate and in engagement with the said frame members, cutter teeth mounted in V-shape in the said planer frame and said teeth being mounted in the said 45 planer frame in two sections so that the forward section thereof will form a line of cleavage through a road surface irregularity prior to the coming in contact of the second set of cutters with the said surface 50 irregularity, and means mounted on the said frame members for pivotally adjusting the opposite sides of the planer frame relative to the said frame members.

5. In a road scraper, the combination of 55 spaced frame members, a planer frame mounted intermediate the said frame members, cutter teeth supported by and arranged in V-shape upon the said planer frame, the 60 said teeth being mounted in recesses formed in said planer frame in stepped expanding relation from the forward to the rearward end thereof, means mounted in each recess for locking the cutter bar therein, and means 65 for separately adjusting the sides of the

planer frame vertically relative to the said frame members.

6. In a road scraper, the combination of a pair of spaced frame members, a planer frame mounted intermediate and in engagement 70 with the said frame members, cutter teeth supported by and arranged in V-shape upon the said planer frame, the said cutter teeth members being mounted in recesses formed in stepped expanding relation from the forward 75 to the rearward end of the planer frame and comprising a front and a rear section, the front section of bar cutter members to form a line of cleavage through a road surface irregularity prior to the coming in contact of 80 the second set of bar cutters with the said surface irregularity, and means for independent adjustment of the sides of the planer frame vertically relative to the said frame members.

7. In a road scraper, the combination of 85 spaced frame members, a planer frame mounted intermediate the said frame members, a V-shaped cutter supported by the said planer frame, an inverted U-shaped frame mounted on the said spaced frame members, 90 means mounted on the inverted U-shaped frame member and connected with the corners of the opposite sides of the said planer frame for separately adjusting the opposite sides of the planer frame vertically relative to the 95 said frame members, and the said planer frame being formed curved at its engaging sides so as to engage the said spaced frame members in any adjusted position to hold the 100 said planer frame from lateral movement relative to the said frame members.

8. In a road scraper, the combination of a pair of spaced frame members, a planer frame mounted intermediate the said frame members, means for pivotally supporting the said 105 planer frame at the corners thereof, and the said planer frame being formed curved at its sides, the said curves being of a diameter equal to the distance from the point of pivotal support of the opposite sides of the said 110 planer frame, and means connected with the pivotal supports for separately adjusting the sides of the planer frame vertically relative to the said frame members.

9. In a road scraper, comprising a planer 115 frame, a plurality of bar cutter members mounted in recesses formed in stepped expanding relation from the forward to the rearward end of the planer frame; means to lock said cutter members in said recesses; and spaced chamfered block members mounted in the recesses to the rear of the said cutter members to prevent vertical displacement of said cutter members.

10. In a road scraper, the combination of 120 a pair of spaced frame members; a planer frame mounted intermediate the said frame members, means mounted on said frame members for adjusting the planer frame vertically relative to said frame members; and the said 125

planer frame being formed at its sides so as to engage the said frame members in any adjusted position to prevent relative lateral movement of the planer frame and the frame members.

5 11. In a road scraper, comprising a planer frame, a plurality of bar cutters mounted in recesses formed in stepped expanding relation from the forward to the rearward end of the planer frame, blocks engaging said cutter members, means to secure said blocks to said planer frame, there being bores formed in the planer frame at the rear of the recesses for receiving the cutter members; and chamfered block members mounted in said bores and engaging said cutter members.

10 12. In a road scraper comprising a planer frame, a plurality of bar cutters mounted in recesses formed in stepped expanding relation from the forward to the rearward end of the planer frame, there being bores formed in the planer frame at the rear of the recesses for receiving the cutter members, chamfered block members mounted in said bores and engaging said cutter members; and means for securing said cutter members in said recesses and against said chamfered block members.

15 13. In a road scraper comprising a planer frame, a plurality of bar cutters mounted in recesses formed in stepped expanding relation from the forward to the rearward end of the planer frame, there being bores formed in the planer frame at the rear of the recesses for receiving the cutter members, chamfered block members mounted in said bores and engaging said cutter members, block members engaging said cutter members; and means extending from said planer frame and extending through said block members to lock said cutter members in said recesses and against said chamfered block members.

20 Signed at Los Angeles, California, this 1st day of July, 1926.

EARL A. WHEELER.
